UNITED STATES PATENT OFFICE

95,164

DESIGN FOR A CASING FOR AN OIL ENGINE

William Arthur Weaver, Coventry, and Mervyn
Hamilton-Fletcher, Studland, England

Application July 18, 1934, Serial No. 52,630

Term of patent 14 years

To all whom it may concern:

Be it known that we, William Arthur Weaver, a subject of the King of Great Britain, residing at Cox Street, Coventry, in the county of Warwick, England, and Mervyn Hamilton-Fletcher, a subject of the King of Great Britain, residing at Studland Manor, Studland, in the county of Dorset, England, have invented a new, original, and ornamental Design for a Casing for an Oil Engine, of which the following is a specification, reference being had to the accompanying drawing, forming part thereof.

In the drawing:

Fig. 1 is a perspective view of the article from one side, and

Fig. 2 is a perspective view from the other side.

What we claim is:

The ornamental design for casing for an oil engine, as shown.

WILLIAM A. WEAVER.
MERVYN HAMILTON-FLETCHER.
